A. VASSELLI,
SPEED REGULATOR.
FILED JUNE 9, 1919.

Patented Jan. 9, 1923.

UNITED STATES PATENT OFFICE.

ANTHONY VASSELLI, OF NEWARK, NEW JERSEY, ASSIGNOR, BY MESNE ASSIGNMENTS,
TO HARRIMAN NATIONAL BANK OF THE CITY OF NEW YORK, TRUSTEE.

SPEED REGULATOR.

Application filed June 9, 1919. Serial No. 302,766.

To all whom it may concern:

Be it known that I, ANTHONY VASSELLI, a citizen of the United States, and a resident of the city of Newark, county of Essex, and 5 State of New Jersey, have invented a certain new and useful Improvement in Speed-Regulators, of which the following is a specification.

My invention relates to speed regulating posts for talking machines, of the type 10 wherein a rotary element provided with an index finger cooperating with a scale is employed for indicating to the operator the position at which the speed regulating brake 15 of a spring motor is set whereby the motor may not run beyond the speed indicated on the scale.

The object of the invention is to provide an effective speed regulator, which will be 20 easy to install, and which will not get out of order.

A further object of the invention is to provide means of the character herein described, simple in construction, thoroughly 25 reliable and efficient in its purpose, positive in operation, and inexpensive to manufacture.

With these and other objects in view to be 30 more fully set forth hereinafter the invention consists in the novel construction, combination of elements, and arrangements of parts which will be exemplified in the construction hereinafter described in the specification and illustrated in the accompanying 35 drawings considered together or separately.

The inventive idea involved is capable of receiving a variety of mechanical expressions, one of which for the purpose of illustrating the invention, is shown in the accompanying drawings.

The invention will be first described in connection with the accompanying drawings illustrating one embodiment of my invention, wherein similar reference characters 45 are used to designate corresponding parts throughout the several views, and then more specifically defined and indicated in the appended claims.

In the drawings:—

50 Fig. 1 is a plan view;

Fig. 2 is a side elevation;

Fig. 3 is a similar view at right angles to the position shown in Fig. 2;

Fig. 4 is a section on the line 4—4 of 55 Fig. 1;

Fig. 5 is a section on the line 5—5 of Fig. 4; and

Fig. 6 is a section on the line 6—6 of Fig. 4.

In carrying out my invention, I provide 60 an index plate 1 which is secured to the top of the motor board of a talking machine. Secured to the plate, as by riveting, is a short tubular element 2, provided with a forked extremity 3. Within the tubular 65 member is a rotatable stem 4 which carries at its upper end a milled head 5 and an index finger or pointer 6. The fork 3 is on the opposite side of the plate 1 from the head and finger. 70

The lower end of the stem 4 is enlarged as at 7, and fitting over the enlargement is a tubular member 8, provided with a spiral slot 9. The upper end of the tube 8 has oppositely disposed slots 11, 11 in which the 75 fork arms 3, 3 engage and prevent rotation of the tubes.

Within the lower end of the tube is secured a plug 12 having a projecting finger 13 which is adapted to engage a slot 14 in 80 one end of a lever 15. The lever 15 is the usual bell crank lever, one arm of which carries a brake shoe for engagement with the friction disc of the well known spring motor governor to arrest the motor when it attains the speed indicated by the pointer on the plate 1, due to the depression of the arm 15 of the lever, due to the downward movement of the tube 8, due to the rotation of the milled head 5. 85

The fork ends 3, 3 engage the slots 11, 11 and prevent rotation of the tube 8 and cause it to be raised and lowered by the rotation of the stem, through the engagement of the pin or screw 10 with the spiral slot 9. 95

In accordance with the provisions of the patent statute, I have described the principle of my invention, together with the apparatus which I now consider to represent the best embodiment thereof, but I desire it 100 understood that my invention is not limited to the particular form of apparatus herein shown and described, as it is obvious that the particular embodiment herein shown and described is only illustrative of my invention, and that other means can be employed to obtain these objects and accomplish these results, without departing from the spirit of my invention. 105

Having now described my invention, what 110

I claim and desire to secure by Letters Patent is as follows:-

1. In a speed regulator in combination, a support, a tubular member carried by said support, a second tubular member contacting with the first member and forming a continuation thereof, interlocking means at the adjoining ends of said members permitting relative longitudinal but preventing relative 10 rotary movement of said members, and operating means to regulate the relative longitudinal movement of said members.
2. In a speed regulator in combination, a support, a tubular member carried by said support, a second tubular member contacting with the first tubular member and forming a continuation thereof, interlocking means at the adjoining ends of said tubular members permitting relative longitudinal but 20 preventing relative rotary movement between said tubular members, a cam slot formed within the second tubular member, and an operating shaft extending within both of said tubular members and means carried by 25 the operating shaft for engaging the cam slot.
3. In a speed regulator, in combination, a support, a tubular member carried thereby, an operating member rotatably carried in 30 said tubular member, a second tubular member carried by said operating member, said

tubular members being of the same external diameter, and means for giving said second tubular member a longitudinal translation when the operating member is rotated including a finger extending longitudinally from one end of one of said tubular members. 35

4. In a speed regulator, in combination, a support, a tubular member carried thereby, an operating member rotatably mounted in 40 said tubular member, and having an enlarged head at its end of greater diameter than the passage through said tubular member, a second tubular member carried by and receiving within it the aforementioned enlarged head, said tubular members being substantially of the same external diameter, 45 interengaging means upon said tubular members and said operating member for causing rotation of the latter to produce a straight line movement of said second tubular member including a finger extending longitudinally from said second tubular member into engagement with said first tubular member. 50

55 This specification signed and witnessed this 2nd day of June, 1919.

ANTHONY VASSELLI.
